UNITED STATES PATENT OFFICE.

JOHN W. SIMPSON, OF SANTA BARBARA, CALIFORNIA.

AIR-NOZZLE FOR LOCOMOTIVE-SANDERS.

1,382,862.

Specification of Letters Patent. Patented June 28, 1921.

Application filed January 28, 1921. Serial No. 440,153.

To all whom it may concern:

Be it known that I, JOHN W. SIMPSON, a citizen of the United States, residing at Santa Barbara, in the county of Santa Barbara and State of California, have invented new and useful Improvements in Air-Nozzles for Locomotive-Sanders, of which the following is a specification.

My invention relates generally to sanding devices for locomotives, and more particularly to a nozzle that is positioned in the discharge pipe or conduit that leads from the sand dome and which nozzle is utilized for directing a jet of compressed air into and through the sand outlet pipe for the purpose of blowing sand through said outlet pipe and into and through the pipe that leads downwardly to a point immediately above the track rails.

The principal objects of my invention are, to provide a relatively simple and efficient air nozzle that is capable of being easily and cheaply produced, constructed so that it may be readily applied to the sand discharge pipes or conduits now in general use and to form the passageway through the nozzle so as to eliminate any possibility of its becoming packed with sand to such a degree as to prevent the discharge of air pressure when the sander is operated to effect a discharge of sand onto the track rails.

Locomotive sanders of ordinary construction include a substantially straight air nozzle that is located in the lower portion of a pocket in the discharge pipe that leads from the sand dome and it very frequently happens that the duct in this air nozzle and the air chamber immediately beneath said nozzle become filled with sand and the latter, as a result of vibration while the locomotive is in service, becomes packed to such a degree as to prevent the compressed air, when turned on through the supply pipe leading to the sanding device, from blowing through the sand discharge pipe and performing its functions in the intended manner.

It is the purpose of my invention to provide means in the form of a specially formed air inlet nozzle that will entirely eliminate the possibility of failure of the sanding device to operate due to packing of the sand in the nozzle or air inlet chamber associated with the sand discharge pipe, and to this end I propose to provide an air nozzle having a trap which will prevent the accumulation of any appreciable amount of sand in

the passageway through the nozzle and consequently eliminating a source of trouble that very frequently occurs in the sanding devices now in general use.

With the foregoing and other objects in view, my invention consists in certain new and novel features of construction and arrangement of parts that will be hereinafter more fully described and claimed and illustrated in the accompanying drawings, in which—

Figure 1 is a rear elevational view of a locomotive sand dome with its sand discharge pipe or duct and which latter is equipped with an air inlet nozzle of my improved construction.

Fig. 2 is a side elevational view of the sand dome and showing the sand outlet pipe therefrom and the compressed air pipe that leads to said sand outlet pipe.

Fig. 3 is an enlarged vertical section taken approximately on the line 3—3 of Fig. 2.

Fig. 4 is an enlarged plan view of an air nozzle of my improved construction.

Fig. 5 is a vertical section taken on the line 5—5 of Fig. 4.

Referring by numerals to the accompanying drawings, which illustrate a practical embodiment of my invention, 10 designates the shell of a locomotive boiler, 11 the sand dome, 12 the tubular member that leads from the lower end of the sand dome and serves as a sand discharge pipe, said tubular member being provided immediately adjacent to the dome with a substantially U-shaped portion 13 that performs the function of a sand trap and leading from the outer end of the tubular discharge member 12 downwardly to a point immediately above the track rail that is traversed by the locomotive wheels, is a sand conveying pipe 14.

Depending from the bottom of the trap portion 13 of the sand discharge pipe 12 is a relatively small housing 15 provided with a chamber 16, and leading thereto from a suitable source of compressed air supply is a pipe 17 which serves to convey compressed air to the sanding device and the passage or flow of compressed air through this pipe is controlled by a suitable valve preferably located in the locomotive cab.

My improved air nozzle is seated in the wall of member 13 immediately above the compressed air chamber 16 and projects upwardly into the passageway through the U-shaped member 13, and said nozzle in-

cludes a substantially rectangular body 18, preferably formed of metal and provided with a depending externally threaded shank 19 that is screw seated in the wall between chamber 16 and the passageway through member 13.

Formed through body 18 and shank 19 is an air passageway 20 the upper end of which is closed in any suitable manner, preferably 10 by means of a plug or screw such as 21, and formed in the upper portion of body 18 immediately to one side of and parallel with said passageway 20 is a short duct or passageway 22, the same extending a short distance downwardly through the body 18.

Formed in the lower portion of the body 18 and establishing communication between the lower end of duct or passageway 22 with the upper portion of passageway 20, is a duct 20 or passageway 23, the same being inclined so that it occupies an angle of approximately 45° with respect to a horizontal plane and the lower end of this duct or passageway is closed in any suitable manner preferably 25 by means of a plug or screw such as 24, thus the air passageway through the nozzle and which passageway includes the ducts 20, 22 and 23 is substantially Z-shaped, and the inclined portion 23 of the duct disposed between the vertical portions 20 and 22 forms a trap that will receive and retain a relatively small portion of sand and consequently preventing the passage of any considerable amount of sand downwardly 35 through the nozzle into the air chamber 16 and which action, it will be understood, would form a sand plug of such volume and stability as would prevent the passage of compressed air into and through the sand- 40 ing device in the usual and desired manner.

By thus providing a trap in the air nozzle, the lower portion of the passageway 20 in

the nozzle and the chamber 16 are always free from sand and when the compressed air valve in supply pipe 17 is opened, said air is 45 free to pass through chamber 16 in the lower portion of duct 20 and the force of said air will expel the relatively small amount of sand within the ducts 23 and 22 and will blow sand from the outer portion of the 50 chamber within trap 13 downwardly through discharge pipe 14.

An air nozzle of my improved construction is comparatively simple, is applicable for use in connection with the sanding devices now in general use upon locomotives, and said nozzle is effective in preventing the sanding device from becoming inoperative 55 due to packing of the sand within the air nozzles and within the compressed air chamber to which said nozzle is directly connected.

It will be readily understood that minor changes in the size, form and construction of the various parts of my improved air nozzle 60 may be made and substituted for those herein shown and described without departing from the spirit of my invention, the scope of which is set forth in the appended claim.

I claim as my invention: 70
The combination with a locomotive sand discharge pipe having a substantially U-shaped trap, of an air inlet nozzle located in the lower portion of said trap and comprising a plug that is screw seated in the 75 bottom of said trap, said plug being provided with a pair of vertically disposed ducts that are offset with respect to each other and an intermediate inclined duct connecting the inner ends of said offset ducts. 80

In testimony whereof I have signed my name to this specification.

JOHN W. SIMPSON
